(57) **CLAIM**

The ornamental design for a medical training device for a cardiac septal occluder, as shown and described.

DESCRIPTION

FIG. 1 is a top plan view of a medical training device for a cardiac septal occluder showing our new design;

FIG. 2 is a bottom plan view thereof;

FIG. 3 is a rear elevation view thereof;

FIG. 4 is a front elevation view thereof;

FIG. 5 is a right side elevation view thereof;

FIG. 6 is a top, right side perspective view thereof;

FIG. 7 is a front, perspective view thereof; and,

FIG. 8 is a top, left side perspective view thereof.

The broken lines shown in all views are to illustrate environment only and form no part of the claimed design.
